(57) **CLAIM**

The ornamental design for a clamping and locating angle, as shown and described.

DESCRIPTION

FIG. 1 is a left side, front, top perspective view of a first embodiment of a clamping and locating angle, showing my new design;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof;

FIG. 7 is a bottom plan view thereof;

FIG. 8 is a rear, left side, top perspective view thereof; and

FIG. 9 is a right side, front, bottom perspective view thereof;

FIG. 10 is a right side, front, top perspective view of a second embodiment of a clamping and locating angle, showing my new design;

FIG. 11 is a front elevation view thereof;

FIG. 12 is a right side elevation view thereof;

FIG. 13 is a rear elevation view thereof;

FIG. 14 is a left side elevation view thereof;

FIG. 15 is a top plan view thereof;

FIG. 16 is a bottom plan view thereof;

FIG. 17 is a right side, rear, top perspective view thereof; and,

FIG. 18 is a left side, bottom, front perspective view thereof.
